UNITED STATES PATENT OFFICE.

CHARLES P. DEARBORN, OF BOSTON, MASSACHUSETTS.

HINGE FOR AWNING-BLINDS.

SPECIFICATION forming part of Letters Patent No. 231,655, dated August 31, 1880.

Application filed April 23, 1880. (Model.)

To all whom it may concern:

Be it known that I, CHARLES P. DEARBORN, of Boston, county of Suffolk, State of Massachusetts, have invented an Improvement in 5 Blind-Hangings, (Case B,) of which the following description, in connection with the accompanying drawings, is a specification.

This invention relates to improvements in blind hangings or hinges of that class which 10 permit the blinds to swing separately about a vertical pivot, or both turn out at bottom on horizontal pivots at the tops of the blinds to permit the blinds to serve as an awning.

In a patent of the United States heretofore 15 granted to me, No. 202,935, I have shown and described a lower hinge the socket portion of which is made vertically movable, so as to remove the said socketed part from the hinge-pintle when it was desired to turn outward 20 the bottom of the blind to enable the blind to serve as an awning, the entire weight of the blind during such operation resting upon the upper hinge.

My present invention is an improvement on 25 the hinge described in the said patent, and relates, chiefly, to providing a hinge of this class with locking devices to prevent it from being lifted or disengaged from the pintle by a person outside the house. I have also shown the 30 said socket portion pivoted on a stud, so as to move in the arc of a circle, which makes a stronger, more easily operated hinge, and one of less cost.

Figure 1 represents an interior view of the 35 blind and casing, the blind being supposed to be closed, the locking device having been disengaged from the movable socket portion, so that it may be lifted; Fig. 2, a right-hand side view of Fig. 1. Fig. 3 shows the socket portion lifted from the pintle and the blind turned 40 partially outward, as for an awning. Fig. 4 is a rear elevation of Fig. 1. Figs. 5 and 6 show the upper and lower hinges opened; Fig. 7, a modification of the hinge shown in 45 the other figures; and Fig. 8, a detail of part of the lower hinge, to show more clearly the provision herein made to lock the blinds open when the blinds swing, as usual, on the vertical pintles.

50 In the drawings, *a* represents the casing or

fixed part of the building, and *b* the side rail of a blind.

The upper hinge, *c d e f*, is as in my patent referred to, *c* carrying the upper pintle, *d* being attached to the blind, the socket *e* being 55 connected loosely with part *d* by a pivot, *f*, as in Fig. 3. The member *g* of the lower hinge, to be attached to the casing or building, has a pintle, *h*, and a lateral projection, with a fastening-stud, *i*, or notch, and a stop, *j*, to 60 prevent the blind being accidentally lifted from the upper hinge. That member of the lower hinge to be connected or move with the blind is composed of a plate, *k*, having holes 2 to receive screws, by which to attach it to 65 the blind, and of a movable socket part, *l*, preferably pivoted to the part *k* by a pivot, *z*, so that the said socketed portion may be turned in the arc of a circle when being lifted from the pintle. This socketed part has one part 70 of it (marked *m*) prolonged to form one portion of the socket-part locking device, the other co-operating part being a movable stop, *n*.

In Figs. 1 to 6 the part *m* is made as a hook, and the part *n* as a segmental plate pivoted at 75 4, and having a pin, 5, by which to turn the plate. When the plate *n* is as in dotted lines, Fig. 1, the socketed part cannot be lifted or moved from its engagement with the pintle from the outside of the blind; but when as in 80 full lines, Fig. 1, the socketed part may be turned on the pivot 3 and lifted or removed from the top of the pintle, to permit the lower end of the blind to be turned outward, as in Fig. 3.

The socket part *l* has a hand-projection, *o*, to be grasped by the person opening the blind, if it is desired to detach the socket portion from the pintle. Extending from the lower end of the socket portion is a short arm, *p*, which, 90 when the blind is opened, falls behind the projection *i*, before referred to, of the fixed member *g*, or into a notch in the said member, to hold the blind open when swung outward on the vertical pintles. When the blinds are to be 95 closed from the inside the plate *n* or *n*² is disengaged from the socketed part *l*, permitting the latter to be lifted just far enough to elevate the projection *p* above the projection *i*. This obviates lifting the blind when it is to be un- 100

fastened and closed, which is customarily done in blinds now commonly in use of the Charles Parker class, such lifting of the blind to enable it to be closed resulting very frequently in lifting it a little too far when the blind is thrown from the building.

The device for holding the two blinds together when being used as an awning may be of any usual construction.

10 In Fig. 7 I have shown a modification illustrating the application of a locking device for the socketed part when the same is slotted, as at 6, to slide vertically on pins 7, as illustrated in my patent referred to. In the said figure 15 the movable member of the locking device (therein distinguished by the letter n^2) has a slot to permit it to be guided by and turn on a pin, 8, when, as in full lines, the part n^2 meets the upper part of the movable socketed member 20 and locks it, so that it cannot be lifted; but when in the position shown in dotted lines the socketed part may be freely lifted from the pintle.

I claim—

25 1. The pintle member g , provided with the projection i , combined with the socket portion l , made detachable from the pintle while the weight of the blind is supported by the upper hinge, and provided with a projection, p , to co- 30 operate with the projection of the fixed mem-

ber g , to hold the blind securely when opened, substantially as described.

2. In a hinge for awning-blinds, the plate k and the socket portion l , pivoted thereon, as described, and provided with the hand-projection located at the inner face of the blind, to permit it to be turned about the pivot 3 and disengage the socket from the pintle, while the upper hinge supports the weight of the blind, in combination with the blocking device, to co- 40 operate therewith and prevent the socket part from being lifted from the pintle, as set forth.

3. In a hinge for awning-blinds, the plate k and socket portion l , pivoted thereon, provided with the hand-projection o , located at the in- 45 nerface of the blind, substantially as described.

4. In a hinge for awning-blinds, the plate k and socket part l , pivoted thereon, provided with a handle portion, o , and hooked projection m , combined with the movable plate, to en- 50 gage and hold the said hooked portion m , substantially as described.

In testimony whereof I have signed my name to this specification in the presence of two sub- scribing witnesses.

CHARLES P. DEARBORN.
